(57) **CLAIM**

The ornamental design for a automotive shifter, as shown and described.

DESCRIPTION

FIG. 1 is a front perspective view of the automotive shifter showing my design;

FIG. 2 is a top plan view thereof;

FIG. 3 is a further front perspective view with environment thereof;

FIG. 4 is a front elevation view thereof;

FIG. 5 is a rear elevation view thereof;

FIG. 6 is a first side elevation view thereof; and,

FIG. 7 is a second side elevation view thereof.

The broken lines showing the vehicle interior and portions of the automotive shifter form no part of the claimed design.

1 Claim, 7 Drawing Sheets
